Primary Examiner — Leanne Was-Englehart*(74) Attorney, Agent, or Firm* — Saidman DesignLaw Group, LLC(57) **CLAIM**

The ornamental design for a theater, as shown and described.

DESCRIPTION

The sole FIGURE is a front perspective view of a theater showing our new design.

The peripheral dashed broken lines illustrate a field of view and form no part of the claimed design. The broken lines within the peripheral dashed broken lines and the faded area within those broken lines illustrate portions of the theater which form no part of the claimed design.
